METHOD OF PACKAGING HANGERED GARMENTS

Charles B. Blessing, Oakland, Calif., assignor to
 Blessing Packaging Company, a corporation of
 California

Original application May 10, 1949, Serial No.
 92,259. Divided and this application July 5,
 1949, Serial No. 103,027

1 Claim. (Cl. 53—5)

1

This application contains divisional subject matter taken from application Serial No. 352,897, filed August 16, 1940, now abandoned, Serial No. 654,400, filed March 14, 1946, now abandoned, and Serial No. 92,259, filed May 10, 1949, and which is now Patent No. 2,479,552, granted August 23, 1949.

This invention relates to the formation of a bag or envelope about an article; the invention will be particularly described as it has been applied to the packaging of garments, but it is broadly applicable to the packaging of any other suitable item.

It has been usual heretofore to package a cleaned garment in a previously formed bag. This operation is slow and expensive, requiring a pre-formed stock of bags of different lengths which must be selected to fit the length of the garment to be protected. In accordance with the present invention, a roll of flat tubular stock is provided from which a suitable length is formed as needed into a bag which is positioned about the garment to be packaged, the flat tubular stock being cut to provide opposite cut side portions of the tubular stock and to leave uncut a central portion, each cut side portion being folded and fastened, leaving the central portion intact and providing a connection with the remainder of the tubular stock so that this can be drawn into place preparatory to the packaging of another item. Afterwards, the central portion is severed and the packaged item removed.

It is in general the broad object of the present invention to provide a novel method for the formation of an envelope for a garment or the like from tubular stock.

The invention includes other objects and features of advantage, some of which, together with the foregoing, will appear hereinafter wherein the present preferred form of practicing the method of this invention is disclosed.

In the drawings:

Figure 1 is a schematic view of a machine which can be employed to practise the invention.

Figure 2 is a front view of the machine shown in Figure 1, illustrating the machine in further detail.

Figure 3 is a fragmentary view partly in section of one embodiment of a cutting mechanism and a folding and a stapling mechanism actuator.

Figure 4 is a fragmentary sectional plan view of the cutting and stapling mechanism along lines 4—4 in Figures 3 and 6.

Figure 4a is a section at line 4a—4a of Figure 4.

Figure 5 is a detail of the stapling machine in operated position.

2

Figure 5a is a fragmentary view of the stapling mechanism in retracted position, the folding mechanism also being shown in retracted position.

Figure 6 is a side elevation showing a modified embodiment of the clothes hanger support and fold line control.

Figures 6a, 6b, 6c, 6d, and 6e show parts of the collapsible hanger support of Figure 6.

Figure 7 illustrates a modified mechanism for feeding paper, cutting, holding the center for folding, and actuating the folding and stapling mechanism.

Figures 8a, 8b, 8c and 8d show a further modification of the mechanism for folding and fastening a cover about a supported garment.

Figure 9 illustrates another form of collapsible garment hanger support.

Figure 10 is a perspective view of a complete form of the machine for practising this invention.

Figures 11 and 12 are steps in the method utilized for formation of a bag or envelope while Figure 13 illustrates a completed envelope.

The invention is conveniently practised utilizing a machine such as that shown in Figures 1 and 2 wherein the garment 10 on hanger 12 is hooked on a recess 14 in the upper end of an inclined post 16. The garment hangs to a point 18 opposite a point between graduations 3 and 4. A flat tube of paper 20, made up of two sheets 301 and 302, is drawn from a roll of tubular paper stock 22 and over an upper guide roll 24 out through slot 25 onto the face 26 of frame 28 so that its lower open end 21 stops at a point between graduations 3' and 4', and envelopes the garment, hanger, and post 16, as indicated in Figures 2 and 6, fully covering the garment, and having passed under the cutter 30 for cutting from 32 to 34 on each side of the sheet.

The paper is then cut from 32 to 34 in each direction from center and the corners 36 and 38 are turned inward and fastened as at 40 and 42 by adhesive tape or by suitable staples thus forming a tapered shouldered bag, the same remaining

45 in bond with the supply of stock from 32 to 32. By pulling the paper at the midline the stock is pulled from under the knife 30 and to the full line position of Figure 2. The portion of paper from 32 to 32 is now cut off, leaving the stock ready for

50 the next bag and garment. The completed bag is now pulled fully down over the garment as indicated at 18 in Figures 2 and 6.

To remove the garment the operator grasps the upper end of the post 16 and the hanger hook 44, 55 tilts the post and garment forwardly and slips the garment, hanger, and bag, endwise away from

the pivot 46. A suitable spring 48 returns the post to stop 50 which spaces the post from the face 26 of the frame 28.

The bag 52 so made can be slipped from the garment downwardly when in the customer's closet, it being necessary only to break the tapes 40 and 42 or to remove the staples; the corners 38 do not dog-ear. Obviously, the steps outlined can be practised with suitable manual operations and with various mechanical devices.

The distances between the graduations 1 and 1', and between the graduations 2 and 2', and so on in Figure 2, represent the distance between the top of the hanger 12 and the cutter 30 so that when the finished bag is pulled down it will cover the garment to the correct length, avoiding an oversupply of covering and also avoiding a shortage of covering.

Fold lines 54 and 56 are defined, in this modification, by the points 32 and the break may be effected over pivoted barriers 58 biased to lines 54' and 56' by springs 60 against stops 62. When the fold has been effected the barrier members are removed from their position within the fold by rotation inwardly, downwardly, and outwardly to slip out of the notches 64 incident to downward pull on the bag 52 to position of Figure 2.

Member 16 and the spring 48 are preferably of light weight and comparatively weak action respectively in order to protect the bag against tearing in the event the operator lifts the hanger out of 14 and pulls the post 16 against the bag, in which event the post will simply deflect forwardly and allow the bag to slide off the same. The inclination of the post 16 is to provide for keeping the post in stable position even though several suits or other garments are hung thereon, leaving the center of gravity of the post and its load rightward of the pivot 46 as viewed in Figure 1. A plurality of rolls of tubular paper 22 are provided simply to render the machine a storage point for a reserve supply of the tubular stock.

While the cutting may be effected by many desirable types of cutting devices, the preferred embodiment of cutting device 30 as illustrated in Figures 1, 2, 3, 4 and 10, is carried by a frame 66 attached by feet 68 to plate 26 at opposite ends of blade-groove, or slit, 70. A blade carrier 72 is movable to the right in Figure 3 and down toward the slit 70 and along it, to carry the cutting blades 76 through the paper which lies through the passage 78 between the frame 66 and the face plate 26. Pins 74 fastened in blade carrier 72 pass through cam slots 80 in the frame 66. Movement of the carrier 72 to the right in Figure 3 causes the blade tips 76' to move rapidly down along path indicated by the dotted lines 82, and then in a slightly inclined direction along the lines 84 to cut the stock from 32 to 34 as shown in Figure 2. The carriage and movement of a second blade carrier 72' is like that of carrier 72 except that it moves to the left in Figure 2 to cut the paper from 32 to 34, as at the left side of the stock in Figure 2. The advantage of moving in opposite directions from the center is that there is no tendency to wrinkle the stock. The advance of the blade into the stock while point 76' follows path 84 insures that all points along the blade cut paper thus distributing the wear on the cutting edge. Several blades are used so that each needs to move only slightly more than its own length, reducing the swing of operating members. Reciprocation of the blade carriers in opposite directions may be accomplished at a single operation by central crank pin 75

86 around the axis of which rotate the crank arms 88 to the ends of which are linked the links 90 and 90' freely rotating on pins 92 and 92' carried by the blade carriers 72 and 72'. Rotation of 88 causes the movement of the carriers in opposite directions. Pin 86 finds bearing support in the frame 66 and a supporting bracket 94 carried by the frame, as shown in Figures 3 and 4. Blades 76 are removably secured to the carrier by thumbscrews 96.

The movement of the blade carriers may be effected by fastening pin 86 to arm 88 and connecting the pin 86 to a lever 98 for rotation to effect cutting. This action may, however, be effected from the end of the cutter by a link 100 pivoted to the carrier 72 and to a lever 102 pivoted at 104. This lever when actuated will cause movement of the blade carriers in opposite directions. The arms 88 are enclosed by a housing bracket 106.

The folding operation is preferably effected mechanically, as by hinging a portion of the plate 26 beneath the foldline, as shown at 108, the triangular cut-out flap 112 leaving a strip 110 adjacent the cutting groove 70. The operation of the flap 112 is effected from the lever 102 through a transversely sliding link 114. A bracket 116 is secured to the flap 112 and joined to the reciprocating member 114 by a pitman 118 and universal joints 120 and 122 whereby reciprocating movement of the slide member 114 produces rotation of the flap from the dotted-line position in Figure 4 to the full-line position of Figure 4 to cause a fold in the stock along the line 54. A lost motion linkage at 124 provides that the flap 112 is operated only after the blades have cut the paper. Slots 80 permit over travel of the blades after cutting to permit the folding operation. Retraction of the blades is effected before the flaps 112 return to their position flush with the plate 26. The foldline terminus at 64 is assured by the bowed leaf spring 58', which permits the stock 52 to slide thereunder incident to feeding the stock and which is flattened by the plate, offering no considerable resistance. A spiral spring 60' locates and relocates the member 58' at the desired radius.

It is desired to fasten the fold near the foldline 54, and this may be done with a conventional stapler 126 having its anvil portion 128 secured to the plate 26 as by means of a plate 130 having trunnion ears 132 and pivoted to lugs 134 on opposite sides of a recess 136 adjacent the pivot line in the plate 26, said lugs 134 being secured to the plate 26 and providing for the pivoting of the plate 130 parallel to axis of hinges 108 on pivot 148. Plate 130 includes hooks 138 which, with the plate 26, serves to retain the anvil portion 128 in position. A spring latch 140 passes through both the plate 130 and the anvil 128.

The movable portions of the stapler 141 and 142, respectively carrying the pusher and the magazine members, are detachably secured to the flap 112 by trunnion ears 144 and adapter 146 rigidly secured to member 141 and pivoted to said ears 144 by a pin 150 parallel to axis of 108. A recess 136' is provided in flap 112 for the passage therethrough of staples and the stapling head 142. The pivot pins 148 and 150 are so spaced as to ensure that when the stapler is in fastening position, the staple is caused to engage and pass through the paper near the fold made as an incident to the folding operation, as illustrated in Figure 5. The pivots are spread apart for retraction of the staple ejector in the position flush

with plate 26 as illustrated in Figure 5a. The stapler 126 is of such size or so located that it can pass through the opening formed by the folding movement of the flap 112. With the plate 26 in an inclined position the folding and stapling action of the flap 112 is accelerated by gravity, the longer leverage of the plate 112 adding thereto.

By modifying the construction the paper may be entirely cut from the center line CL. The blades 76 are positioned to effect a cut entirely across the stock. Resilient rubber hold-down strips 152 are carried by the carrier bars 72 and 72' and engage the cut-off portion of paper to the points 32, as shown in Figures 3 and 7. After the flaps 112 are returned to starting position, the paper is fed past the knife position by feed mechanism 154 of conventional design carried above the knife position as illustrated in Figure 7 wherein the stock is illustrated as fed over the flap 112.

As illustrated in Figure 7, the flap may be actuated by a slider 114' sliding along the edge of the plate 26 and connected to an arm 116' by a universally connected link 118'. Slider 114' may be connected by a pawl arrangement to the mechanism 154 so that the final movement of the slider feeds the paper sufficiently far so that the operator can engage the same to pull it over the post 16. The timing is such that the flap 112 returns to full line position of Figure 7 before the stock feeds to the upper edge thereof, and such that the rubber hold-down strips 152 are retracted before the stock feed reaches their position so that the stock clears all operating mechanism.

In the modification of Figure 6 the barriers are dispensed with and the same result is obtained by forming the plate 26 with a ridge thereacross at 158 to intersect at the lower fold terminus 64 as indicated in Figures 2 and 4. The paper stock is pulled down over this angle and offers sufficient resistance to deformation on the surface 160 therebelow to prevent the paper from rolling beyond the ridge, while the upper corners 32 are held as in Figure 2 or by the hold-downs 152. The barriers 58' and 58 are thereby dispensed with.

As illustrated in Figure 6 the cutting, folding and fastening may be entirely effected from a foot lever 162 through a pitman 164 and suitable bell cranks 166 and 172 carried by shaft 168 mounted in trunnions 170 on the frame 174 and suitably connected to actuate lever 102 and slider 114 in Figure 3 or connected to actuate lever 102 in Figure 3 and slider 114' in Figure 7. The foot lever 162 is preferably insured a full stroke by a full stroke pawl 176 biased by spring 178 and sliding on stationary notched arc 180 over the extent of which it must slide before being permitted a reversal.

In order to prevent the tearing of bags by the negligent operator an improved form of post is provided and shown in Figure 6 to comprise telescoping members 182, 184 and 186. The stationary telescoping member 182 is fixed to the base 188 of the supporting structure 174 and is provided with a generally vertically disposed slot 192 for the reception therethrough of a pin 190 and a pin 196 on the telescoping member 184 and 186 respectively. Slot 192 terminates in a ledge 194 adapted to receive and support the pin 190 in a slight swell. The ledge communicates from its offset position with the vertical slot by a camway section 198. This camway is provided

to insure entry of the pin 190 into recess 194 in response to an upward pull on movable telescoping member 184, and also to insure its removal from said recess when it is required that the post collapse as will be explained presently.

Telescoping member 184 is provided with a vertical slot 200 for the reception of the pin 196 fitted in the lower end of the member 186. Slot 200 lies adjacent the pin 190 and provides a recess 202 beneath the pin 190 and a hooked recess 204 for reception of the pin 196'. The upper end 206 of member 186 is beveled and provided with a hanger receiving slot 208. This slot may be spiraled as shown in Figure 6e for a purpose to be explained.

Pin 196 and slot 200 are smaller than pin 190 and slot 192. With pin 190 in recess 194 slot 200 lies in alignment with the lower side 210 of camway 198. Pin 196 is long enough to extend partially outwardly of slot 200 and into the slot 192. In order to permit passage of pin 196 to slot 192 the grooves 212 and 214 are provided for its passage from either of its possible angular positions with respect to the base member 182.

Considering the post to be extended upwardly and the pins 190 and 196 in their respective recesses 194 and 204, the post is collapsed by turning the top member, as by means of pulling the hanger straight up through the spiral slot 216. Such turning of the member 186 causes at least one of the pins 196 or 194 to move out of its recess. The weight of the member or members carried by the pins released causes the member or members to drop.

Assuming that only pin 196 is released from its recess 204 by the rotation of the topmost member it will be clear that the member 186 drops and pin 196 follows slot 200, passes through groove 214 and strikes on cam surface 210. Since the pin 196 is in engagement with the left side of slot 202 and traveling with considerable energy, the reaction of the cam 210 is to move the member 184 so that slot 200 moves toward registry with slot 192 and so that pin 190 moves into camway 198. Accordingly, member 184 drops in response to its release by member 186.

Because pin 190 must slide in slot 192, slot 200 moves past registry with slot 192. Since pin 196 is now in slot 192 the recess 202 permits rotation of the member 184 relative to pin 196 at the time pin 186 strikes cam 210. Member 186 and 184 move down together. On the up movement sections 184 and 186 may move together, provided pin 196 stays in recess 202. In this case pin 190 is forced into recess 204 and pin 196 passes on through grooves 214. If pin 196 precedes pin 190 upwardly, the latching is effected by manually rotating the pins into the ledge recesses.

If it happens that section 184 is first to release in the collapse of the standard, it pulls pin 196 against the cam 210 and releases member 186 to travel down in section 184, member 196 being retractable into member 186 to permit it to clear member 182. To this end member 196 is mounted on the leaf spring 195 retractable into recess 218 in member 186.

By providing the spiral notch 216 in member 186 the slight upward and rotational thrust produced by the upward pull of the hanger produces a sufficient rotation and lift of the member 186 to release it first without releasing the member 184. The entire stand is insured to drop out of the bag 52 whichever section is released.

The standard must be extended to its full length in order to insure that the fabrication of

the bag always occurs at a definite distance above the garment and so that the bag is not too long. To this end it will be noted that the release of member 186 prior to the time either pin is seated permits the dropping of both members to the fully retracted position. Inasmuch as member 186 forces member 184 to extend itself first, the release of member 186 before it enters recess 204 results in collapse of member 184 also. If member 182 should happen to be released first, pin 196 is released by cam groove 213 which is in the path of its movement and directed to force pin 196 into groove 208 and to slide inside tube 182 until it is free to move laterally in recess 202.

Another method of making a bag corner is illustrated in Figures 8a to 8d. After the paper is cut the corners are rolled and then the rolls are flattened and fastened as is shown in Figure 8d. This makes a strong, rigid joint. The mechanism used replaces the flaps 112 and comprises a slide member 227 traveling in a dovetail track 228 in plate 26. After the cut of the paper is made, the mechanism, including folding scroll 226, slides against the corner 34 in a direction which is normal to the desired foldline 56. The paper so engaged rolls within the scrolls and, when a sufficient rolling has been effected, the fastener stapler 126 is operated to flatten the paper and fasten it together.

I claim:

The method of packaging a hanger garment which does not have sufficient rigidity to stand alone comprising supporting the garment on a hanger, said hanger being supported from a point below the lower level of the garment so that the garment is freely hanging in a vertical position

and spaced above floor level, drawing a portion of tubular stock partially over both the hangered garment and the support for the garment from a length of tubular stock which is substantially longer than the desired enclosure, transversely severing edge portions to leave the stock unsevered in a central portion only, folding over the severed edge portions to close the severed edges, securing each folded over edge portion to the adjacent tubular stock to seal an end of the stock except at said unsevered central portion and form a bag about the article, drawing the so formed bag into place on the article and finally severing the unsevered central portion.

CHARLES E. BLESSING.
